ISAAC M. SHARP, OF SAN FRANCISCO, CALIFORNIA.

OIL BURNER.

Application filed April 1, 1919. Serial No. 286,626.

To all whom it may concern:

Be it known that I, ISAAC M. SHARP, a citizen of the United States, residing at San Francisco, in the county of San Francisco and State of California, have invented new and useful Improvements in Oil Burners, of which the following is a specification.

This invention relates to oil burners and particularly to burners of the rotary type.

10 One of the objects of the present invention is to provide an oil burner of the rotary type in which the oil is first atomized and projected by centrifugal action and then further atomized and projected forwardly into the furnace by means of an annular air or steam blast, as will hereinafter be fully described.

Another object of the invention is to provide a burner structure which permits withdrawal of the fuel atomizer and the parts connected therewith when the burner is not in operation.

Another object of the invention is to provide means for automatically shutting off the oil supply when the atomizer is withdrawn.

Another object of the invention is to provide a novel form of centrifugal fuel atomizer and in conjunction therewith means for regulating the volume of air or steam employed for secondary atomization.

Further objects will hereinafter appear.

The invention consists of the parts and the construction, combination and arrangement of parts as hereinafter more fully described and claimed, having reference to the accompanying drawings, in which—

Fig. 1 is a central vertical, longitudinal section through the burner.

40 Fig. 2 is a cross section of the same.

Fig. 3 is a detail view of the centrifugal atomizer.

Referring to the drawings in detail, A indicates a burner casing which in this instance is adapted to be secured to a furnace front by means of an annular flange 2. The casing A is cylindrical in cross section, as shown in Fig. 2 and is provided with a central passage 3 and a plurality of smaller passages 4 arranged in cylindrical formation around the central passage 3. Slidably mounted on the outer end of the casing A is a head member 5 which is supported by means of a sleeve extension 6. The head member 5 is provided with openings 4* which normally register with the passages

4 and it is also provided with a damper plate 6 in which are formed openings 7, these openings being moved into or out of register with the openings 4* by turning the plate 6 upon a hub-like extension 8 formed on the forward end of the head. The head is otherwise provided with a handle 9 to permit a sliding movement to be imparted thereto when it is desired to withdraw the fuel atomizer, as will hereinafter be described, and it is also provided with means for limiting its movement and for preventing turning movement of the head when the atomizer is withdrawn. This is accomplished by forming a slot 10 in the cylindrical extension 6 through which a stop screw 11 passes. This screw may, however, be entirely removed if it is desired to remove the head member and the parts attached thereto but it otherwise serves the function of limiting the rearward movement of the head.

The main operating parts of the burner are supported by the head member and are practically all positioned within the central chamber 3 of the casing. These members comprise a hollow shaft 12 which is supported in a ball bearing 13 mounted within a hub-like extension 14 secured to the head member or formed integral therewith. Also secured to the head member is a stationary fuel delivering pipe 15 in which is formed a central passage 16. This passage is in constant communication with a port 17 and a pipe 18 carried by the head. This pipe is so arranged as to be received by a passage 19 formed in the casing and it is employed for the purpose of cooperating with a valve 20 which automatically shuts off the oil supply to the atomizer when this is withdrawn. The valve 20 is normally held against the seat 21 by means of a spring 22 and it serves the function of opening or closing a fuel passage 23 formed in the casing, which is supplied with oil from any suitable source by means of a pipe 24. The forward end of the pipe 18 engages the valve 20 when the atomizer is moved into operating position, thereby moving the valve away from its seat and permitting oil to flow thereby into an annular chamber 25. The oil here enters ports 26 formed in the forward end of the pipe and then passes through the pipe 18, ports 17 and the stationary fuel delivering pipe 15, directly into the atomizer generally indicated at B. This atomizer is secured on the forward end of

the hollow shaft and consists of a head member in which is formed an interior chamber 28. The head member is otherwise provided with flared exterior surfaces such as shown at 29 and 30, the flared surface 29 being provided for the purpose of cooperating with a nozzle member 31 which will hereinafter be described. The oil delivered by means of the pipe 15 is equally distributed within 10 the interior chamber 28 by means of a cone-shaped annular flange 32 secured on the outer end of the pipe 15 and the oil thus delivered is discharged radially by centrifugal force through a series of slot-like 15 openings 33, these slot-like openings being formed by cutting spiral-shaped grooves 34 in the outer surface of the atomizer.

For the purpose of rotating the atomizer at a comparatively high speed, I provide a 20 spiral-like vane such as shown at 35. This vane may be secured to the hollow shaft or formed integral therewith and it is actuated by a fluid under pressure such as air or steam, which is admitted through a pipe 36. This 25 pipe is secured on the casing A and may be connected with a fan or pressure blower not here shown or it may be connected with a source of steam supply. The air or steam admitted enters the central chamber 3 and then passes through a series of openings 37 into the nozzle 31. This nozzle is supported by the bearing member 14 by screwing it thereon, as shown at 38. It entirely surrounds the spiral-like vane 35 and its forward end is enlarged, as shown at 31* to partly enclose the atomizer and also to form a support and guide for the forward end of the nozzle. The enlarged portion 31 is slightly less in diameter than the interior 40 chamber 3, to permit a certain proportion of air to discharge therethrough and it is otherwise provided with flaring mouth 39 which is adapted to cooperate with the flaring surface 29 formed on the atomizer to regulate 45 the volume of air passing through the spiral vane 35.

In actual operation, with the head member assuming the position shown in Fig. 1, it can be seen that valve 20 will be forced 50 away from its seat to permit oil to escape and enter ports 26. The oil entering these ports passes rearwardly through the pipe 18, then upwardly through ports 17 and finally passes through the stationary fuel delivering pipe 15 which delivers it to the interior chamber 28 of the atomizer. This is rotating at a high speed when in operation and it will therefore project the oil through the spiral-shaped slots 31 and out into the 55 furnace. The air or steam admitted through pipe 36 is employed for three purposes: first, that of rotating the hollow shaft and the atomizer carried thereby; second, that of supplying a sufficient quantity of air to support 60 combustion; and third, to produce a

secondary atomizing action and to project the atomizing fuel forwardly into the furnace.

The revolving movement required to operate the atomizer is obtained when the air 70 passes through the ports 37 and the spiral vane 35. This air discharges between the atomizer and the nozzle seat 39 and thus passes through the spray of oil projected by the atomizer. The secondary atomizing action 75 is thus obtained as the air discharges with sufficient velocity to further break up the oil and carry it forward into the furnace. It also causes a thorough mixing action which produces a homogeneous mixture adapted to instantly ignite.

The speed of rotation may be regulated by the position of the nozzle 31 by adjusting its position with relation to the atomizer. If the nozzle is moved forwardly by unscrewing it with relation to the bearing member 14 it can readily be seen that the annular passage formed between the atomizer and the nozzle is reduced. This reduces the volume of air passing through the spiral 80 vane and therefore decreases the speed. Conversely, rearward movement of the nozzle will enlarge said opening and therefore permit a freer discharge of air and a greater volume to pass through the vane, thereby 85 increasing the speed. This adjustment is of considerable importance as it materially affects both the primary and the secondary atomization obtained and it also permits a second volume of air to be discharged exterior of the nozzle 31; that is, through the annular passage formed between the forward end of the nozzle and the casing proper.

When the burner is in operation and it is 90 desired to extinguish the fire, it is merely necessary to grasp the handle 9 and pull the head member in a rearward direction. The rearward movement, as previously stated, is limited by the length of the slot formed in 95 the cylindrical extension and the slot is of such a length that the atomizer B will reach a point approximately in alignment with the air delivering pipe 36. Two results are obtained: first, that of protecting the atomizer proper from the intense heat of the furnace when it is not operating; and secondly, that of shutting off the oil supply. The oil supply is cut off the moment the head is pulled rearwardly as the pipe 18 100 secured thereto will move away from the valve 20 and permit this to close down upon its seat and thereby shut off the oil supply. The fire may, however, be instantly started again, if desired, by merely pushing the 105 head forwardly until the position shown at Fig. 1 is reached.

There are many beneficial results obtained by the various adjustments here shown: for instance, longitudinal movement of the air 110

nozzle regulates the air supply exterior thereof or through its interior. Longitudinal adjustment of the head proper permits shutting off or turning on of the oil and it also permits removal of the atomizer to a point where it will not be affected by the intense heat of the furnace and any oil possibly remaining therein carbonized. The spiral grooves 34 formed on the exterior 10 surface of the head are also of importance as they materially assist in rotating the same; that is, the air escaping from the spiral vane and passing over the head will also pass through the grooves 34 and as the air strikes the inclined or angularly disposed spiral walls of the grooves 34, it must be appreciated that rotary movement is materially assisted. The location of the air nozzle is also an important feature; that is, being positioned within the casing proper and surrounding the hollow shaft which forms two air chambers, through which air passes, the volumes through each passage being regulated, to a great extent, by the position of the nozzle with relation to the atomizer. As the air passes through both passages, a cooling effect is obtained which is important, as it prevents overheating and carbonization of the oil. It furthermore retains the bearing 20 cool, thereby preventing excess consumption of lubricating oil or overheating of the same. When the burner is secured to the furnace front by means of a flange 2 and bolts passing therethrough, it can be seen that the jet action caused by the discharging oil and the annular air blast escaping from the nozzle 31, will induce a flow of air through the passages 4. A considerable volume of air is induced by the jet action 30 through these passages and if too great, may be regulated by means of the damper plate 6. This plate should always be turned to closed position when the fire is shut down, as it is not desirable to quickly cool the furnace by permitting a free inflow of air 40 through said passages. The air through pipe 36 is also shut off when the fire is not required, as any volume of air escaping when oil is not delivered, would merely produce a 50 cooling effect within the furnace box.

All heat imparted to the furnace and contained in the brickwork or lining may thus be retained for a long time as it is possible in the present instance to form a, practically speaking, hermetic seal when the burner is not operating.

Another important feature of the present invention is a construction which permits complete removal of the head member. A further important feature is the fact that practically all operating parts are supported by said head member and are thus easily accessible for inspection and repair when the head member is removed. While the bearing member 14 is here shown as a sepa-

rate part, secured to the head member, it is obvious that it may be made integral therewith if desired. I similarly wish it understood that the materials and finish of the several parts employed may be such as the experience and judgment of the manufacturer may dictate of varying conditions may demand.

Having thus described my invention, what I claim and desire to secure by Letters Pat- 75 ent is—

1. An oil burner comprising a casing, a centrifugal atomizer journaled in the casing, an air nozzle surrounding the atomizer and forming an annular discharge passage thereabout, means for delivering air under pressure to said nozzle, an annular seat formed on the exterior surface of the atomizer, a cooperating seat formed in the discharge end of the air nozzle, said nozzle being longitudinally movable with relation to the annular seat on the atomizer to regulate the volume of air discharging between the nozzle and the atomizer. 80
2. An oil burner comprising a casing, a centrifugal atomizer journaled in the casing, an air nozzle surrounding the atomizer and forming an annular discharge passage thereabout, means for delivering air under pressure to said nozzle, an annular seat formed on the exterior surface of the atomizer, a cooperating seat formed in the discharge end of the air nozzle, said nozzle being longitudinally movable with relation to the annular seat on the atomizer to regulate the volume of air discharging between the nozzle and the atomizer, a hollow shaft extending through the nozzle, supporting the atomizer, and means on said shaft and within the nozzle for imparting a rotary movement to the shaft and the atomizer carried thereby. 85
3. An oil burner comprising a casing, a centrifugal atomizer journaled in the casing, an air nozzle surrounding the atomizer and forming an annular discharge passage thereabout, means for delivering air under pressure to said nozzle, an annular seat formed on the exterior surface of the atomizer, a cooperating seat formed in the discharge end of the air nozzle, said nozzle being longitudinally movable with relation to the annular seat on the atomizer to regulate the volume of air discharging between the nozzle and the atomizer, a hollow shaft extending through the nozzle, supporting the atomizer, and means on said shaft and within the nozzle for imparting a rotary movement to the shaft and the atomizer carried thereby. 90
4. In an oil burner of the character described, a centrifugal atomizer, said centrifugal atomizer comprising a head member, a central chamber formed within said head 100

- member, and a series of spiral grooves formed on the exterior face and communicating with the interior chamber.
5. In an oil burner of the character described, a casing having a central chamber formed therein, a hollow shaft journaled in said casing, a centrifugal atomizer carried by said shaft, a nozzle within the chamber surrounding the atomizer and forming an annular discharge passage thereabout, said nozzle being also mounted within the central passage in the casing and having a diameter less than the interior diameter of the central passage to form a secondary annular discharge passage, means for admitting a fluid, under pressure to the casing and for directing it to the nozzle and to the passage formed exterior thereof, said nozzle being longitudinally adjustable with relation to the atomizer to regulate the volume of air discharging between the nozzle and the atomizer, and a spiral-shaped vane member secured on the shaft within the nozzle to impart a rotary movement to the hollow shaft and the atomizer.
10. In an oil burner of the character described, a casing having a central chamber formed therein, a hollow shaft journaled in said casing, a centrifugal atomizer carried by said shaft, a nozzle within the chamber surrounding the atomizer and forming an annular discharge passage thereabout, an annular seat formed in the outer end of the nozzle, an annular seat formed on the exterior surface of the atomizer, said nozzle being longitudinally adjustable with relation to the atomizer, means for delivering air under pressure to the nozzle, and means actuated by said air under pressure for imparting a rotary movement to the hollow shaft and the atomizer.
15. In an oil burner of the character described, a casing having a central chamber formed therein, a hollow shaft journaled in said casing, a centrifugal atomizer carried by said shaft, a nozzle within the chamber surrounding the atomizer and forming an annular discharge passage thereabout, an annular seat formed in the outer end of the nozzle, an annular seat formed on the exterior surface of the atomizer, said nozzle being longitudinally movable with relation to the atomizer, means for delivering air under pressure to the nozzle, means actuated by said air under pressure for imparting a rotary movement to the hollow shaft and the atomizer, a series of spiral-shaped grooves formed in the exterior surface of the atomizer, an interior chamber formed in the atomizer, slot-like openings forming a communication between the exterior spiral grooves and the interior chamber, and means for delivering oil to the interior chamber.
20. An oil burner comprising a casing having a central passage formed therein, a bearing member slidably mounted on the casing, a shaft journaled in said bearing member, centrifugal atomizer secured on the shaft, a nozzle partially surrounding the centrifugal atomizer, means for moving the bearing and the parts carried thereby longitudinally of the casing, means for delivering oil to the atomizer, means actuated by the longitudinal movement of the bearing member for automatically shutting off the oil supply.
25. An oil burner comprising a casing having a central passage formed therein, a bearing member longitudinally adjustable on the casing, a shaft journaled in said bearing member, a centrifugal atomizer on the end of the shaft, a nozzle partially surrounding the atomizer, and means for adjusting said nozzle longitudinally with relation to the bearing member and the centrifugal atomizer.
30. In a burner of the character described, a casing having a central passage formed therein, a centrifugal atomizer mounted in said passage, an air discharging nozzle cooperating therewith, said atomizer and nozzle being longitudinally movable in unison, and means permitting independent longitudinal movement of the nozzle with relation to the atomizer.
35. In a burner of the character described, a centrifugal atomizer comprising an in-

closed head member having a central chamber formed therein, and a plurality of angularly disposed slots formed in the exterior surface of the head member, said slots being so deep as to cut partly through the head member and to communicate with the interior chamber.

13. An oil burner comprising a casing, a centrifugal atomizer journalled in the casing, an air nozzle surrounding the atomizer and forming an annular discharge passage thereabout, a central passage in the casing in which the atomizer and the nozzle is positioned, means for delivering air under pressure to said central passage and to the nozzle to permit air to discharge both interior of and exterior of the nozzle, said nozzle being longitudinally movable with relation to the atomizer to regulate the volume of air discharging through and exterior of the nozzle, and a spiral shaped vane rearwardly of the atomizer and interior of the nozzle, said spiral shaped vane adapted to rotate the atomizer when air is passing through the nozzle.

14. A burner of the character described, a centrifugal atomizer comprising an in-closed head member, a central chamber formed therein, a plurality of slots formed in the exterior surface of the head member, said slots being so deep as to cut partly through the head member and to communicate with the interior chamber.

15. An oil burner comprising a cylindrical shaped casing having a central passage formed therein, a head member forming a closure for one end of the casing and slid-

able longitudinally on the casing, a bearing member and the head extending into the central passage, a shaft journalled in the bearing member, an atomizer secured on the outer end of the shaft, a nozzle carried by the bearing member and forming an annular air passage about the atomizer, said nozzle being longitudinally movable with relation to the atomizer and the bearing member, and means for passing an air blast through and exterior of the nozzle.

16. An oil burner comprising a cylindrical shaped casing having a central passage formed therein, a head member forming a closure for one end of the casing and slid-able longitudinally on the casing, a bearing member and the head extending into the central passage, a shaft journalled in the bearing member, an atomizer secured on the outer end of the shaft, a nozzle carried by the bearing member and forming an annular air passage about the atomizer, said nozzle being longitudinally movable with relation to the atomizer and the bearing member, means for passing an air blast through and exterior of the nozzle, and a spiral shaped vane on the shaft interior of the nozzle adapted to rotate the shaft and atomizer when air is passing through the nozzle.

In testimony whereof I have hereunto set my hand in the presence of two subscribing witnesses.
